UNITED STATES PATENT OFFICE.

PETER NEFF, DONALD COLE, AND ELBERT L. EBERSOLE, OF CANTON, OHIO, ASSIGNEES
TO THE ARCTIC ICE MACHINE COMPANY, OF CANTON, OHIO, A CORPORATION OF
OHIO.

AMMONIA-COMPRESSOR.

1,092,943.

Specification of Letters Patent. Patented Apr. 14, 1914.

Application filed September 25, 1908. Serial No. 454,741.

To all whom it may concern:

Be it known that we, PETER NEFF, DONALD COLE, and ELBERT L. EBERSOLE, citizens of the United States, and residents of Canton, in the county of Stark and State of Ohio, have invented certain new and useful Improvements in Ammonia-Compressors; and we do hereby declare the following to be a full, clear, and exact description of the 10 invention.

The present invention relates to improvements in ammonia-compressors, the object of which is to provide means and devices which will maintain the cylinder cool by 15 the incoming gas and at the same time provide means whereby a compound or double action is produced.

With these objects in view the invention consists in the novel features of construction and combination and arrangements of parts which will be more fully hereinafter described and pointed out in the claim.

In the accompanying drawing: Figure 1 is a vertical longitudinal section of the cylinder illustrating our improvements properly arranged with reference to said cylinder. Fig. 2 is a sectional view taken on line 2—2, Fig. 1. Fig. 3 is a transverse section taken on line 3—3, Fig. 1. Fig. 4 is a view 20 of the cylinder showing parts broken away, also showing one of the heads and caps detached. Fig. 5 is a horizontal sectional view of the chambered head showing the feed pipes properly located.

Similar numerals of reference indicate corresponding parts in all the figures of the drawings.

In the accompanying drawing, 1 represents the cylinder proper, which cylinder is 40 formed of any desired size, reference being had to the capacity of the compressor and as shown it is provided with the integral base 2, designed to be properly connected to the foundation or base plate 3.

Within the cylinder 1 is located the piston rod 4, which piston rod is reciprocated by any well known and common means. Upon the piston 4 are securely mounted the pistons 5, which pistons carry the piston rings 6, said rings are each provided with the seat flanges 7 and the cushion rings 8, but these parts within themselves form no specific part of this invention and we lay no claim to the specific and detailed construction of 55 the pistons and their different parts.

Around the cylinder 1 is located the chamber 9, which chamber is inclosed by the integral casing 10, and the outer wall of the cylinder 1. The casing 10 is provided with the valve connecting flange 11, to which is 60 connected the valve 12, said valve being of any ordinary construction and from which valve leads the ordinary feed pipe, which is extended to and connected with the coils of the refrigeration chambers. This pipe is 65 not illustrated as it will be understood that an ordinary feed pipe is to be employed.

It will be understood that the gas (preferably ammonia) should be kept at as low a temperature as possible during the time 70 the cylinder is being filled and the gas compressed and hence it is of importance that provision be made for maintaining the cylinder at as low a temperature as possible and this invention has more specific reference in keeping the cylinder at a low temperature. For this purpose of keeping the cylinder at a low temperature the central or intake portion of the cylinder is covered with a layer of suitable insulating material, 75 such as cork, sawdust or asbestos 13, over and upon which is placed a metallic sheet connected to the casing 10 or its equivalent.

The ends of the cylinder 1 are closed by means of the chambered heads 15 and 16 to 80 which heads are connected the caps 17, said caps and chambered heads being so arranged with reference to each other that water can be forced through said chambered heads as hereinafter described. To the caps 80 17 are connected the cold water pipes 18, which cold water pipes lead to any source of supply and may be provided with cut off valves 19 of any desired construction. The chambered heads 15 and 16 may be provided 85 with the webs 20, which webs are for the purpose of interrupting the rapid flow of water and at the same time presenting a greater cooling surface, said webs also serving the purpose for strengthening the heads. 100

For the purpose of causing water to enter upon opposite sides of the lower or vertical web of the webs 20, two pipes 21 are provided, which pipes are connected by the cross passage ways 22 formed in the cap 17. When the chambered head becomes filled with water or practically so it is conveyed from the head by means of the outlet pipes 23 located upon opposite sides of the upper web 20 and thence conveyed to the pipes 24, 110

2
to which pipes are connected the spray pipes 25, said spray-pipes being located directly over and above the outer end portions of the cylinder 1. For the purpose of causing the 5 water to flow in a sheet ~~over~~ stream of a width practically equal to the length of the pipes 25 the escape or over flow slots 26 are located in the top or upper sides of the pipes 25. For the purpose of removing the water 10 after it has performed its function the drain pipes 27 are provided, which drain pipes lead to any desired place. For the purpose of observing the overflow of the water, the pipes 27 are provided with the open sided 15 couplings 28, which open sided couplings provide over-flow passages if there should be any backing up of the water. For the purpose of collecting the water that passes from the pipes 25, the flanges 29 are provided, which flanges retain the water and guides the same to the drain pipes 27. Between the pistons 5 and through the shell of 20 the cylinder 1 are formed a series of intake ports or passages 30, through which the gas 25 passes into the cylinder and as the pistons are moved back and forth or reciprocated the gas will be compressed and forced through the valves 31 and thence conveyed through the pipes 32 to the condensers. The 30 pipes 32 are or should be provided with the ordinary valves 33. It will be understood that after the gas has been thus compressed it is in a heated condition, hence the necessity of returning it to the condensers. The 35 valves 31 are so constructed that they will be closed except at such times as the pressure is sufficient to overcome the tension of the springs 34, and the back pressure, at which time the valves are open.

40 It will be understood that by forming two pistons and mounting them upon the piston rod, and locating the intake ports between the pistons the gas will be compressed alternately at the opposite ends of the piston, thereby producing practically continuous 45 compression. In order that the gas may pass through the pistons 5 during what might be termed their backward or idle strokes the piston rings 6 are so connected that there will be a slight relative movement as between the pistons proper and the rings thereby allowing the seat flanges 6 to be disconnected from the seat faces of the 50 pistons.

In Fig. 1 the piston rings are shown seated and unseated or in other words the pistons closed and opened. This feature however forms no specific part of my invention except that it is necessary to provide pistons that will not compress the gas during their 55 backward or idle stroke.

It will be understood that liquid and sediment will accumulate from time to time and settle in the bottom of the chamber 35 and for the purpose of removing this the stop 65 cocks 38 may be provided. Between the extreme end portions of the cylinder 1 and the central or what might be termed middle portion of said cylinder there are spaces that will not become heated as rapidly or 70 to as high a degree as the outer end portions and hence it is unnecessary to provide any means for cooling said parts other than atmospherically cooling and hence the pipes 25 are not necessarily extended to the ends 75 of the middle or insulated portion of the cylinder.

It will be understood that the pipes 25 should be protected and hidden and in order to provide for this the casing 36 is provided. 80 For the purpose of providing easy access to the pipes 25 the casing 36 should be provided with the removable covers 37.

Having fully described our invention what we claim as new and desire to secure 85 by Letters Patent, is—

In a compressor of the class described, a cylinder having a chamber extended for a portion of its length, intake ports formed through the cylinder, said chambered portion of the cylinder provided with insulation and portions of said cylinder atmospherically exposed, chambered heads provided with webs adapted to close the ends of said cylinder, water pipes leading to and 95 from the chambered heads, a piston rod and piston located thereon, said piston adapted to open and close, substantially as and for the purpose specified.

In testimony that we claim the above, 100 we have hereunto subscribed our names in the presence of two witnesses.

PETER NEFF.
DONALD COLE.
ELBERT L. EBERSOLE.
